US0D1063855S

(12) **United States Design Patent** (10) **Patent No.:** **US D1,063,855 S**
(45) **Date of Patent:** **** Feb. 25, 2025**

(54) **ELECTRICAL CONNECTOR ADAPTER**

(71) Applicant: **WANKA TECHNOLOGY LIMITED**,
Shenzhen (CN)

(72) Inventors: **Shuai Peng**, Shenzhen (CN); **Yun Chen**, Shenzhen (CN); **Zhiwei Chen**, Shenzhen (CN)

(73) Assignee: **WANKA TECHNOLOGY LIMITED**,
Shenzhen (CN)

(**) Term: **15 Years**

(21) Appl. No.: **29/881,673**

(22) Filed: **Jan. 5, 2023**

(51) **LOC (15) Cl.** **14-02**

(52) **U.S. Cl.**

USPC **D14/433**

(57) **CLAIM**

The ornamental design for an electrical connector adapter as shown and described.

DESCRIPTION

FIG. 1 is a bottom, front, right side perspective view of an electrical connector adapter, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines in the drawing depict portions of the electrical connector adapter that form no part of the claimed design.
